UNITED STATES PATENT OFFICE.

EDWIN FORREST TAYLOR, OF NEW DECATUR, ALABAMA.

ROTARY ENGINE.

No. 850,450.

Specification of Letters Patent.

Patented April 16, 1907.

Application filed February 16, 1904. Serial No. 193,694.

To all whom it may concern:

Be it known that I, EDWIN FORREST TAYLOR, a citizen of the United States, residing at New Decatur, in the county of Morgan 5 and State of Alabama, have invented certain new and useful Improvements in Rotary Engines; and I do hereby declare the following to be a full, clear, and exact description of the invention, such as will enable others 10 skilled in the art to which it appertains to make and use the same.

In an application for patent filed by me August 22, 1902, Serial No. 120,718, I have shown, described, and claimed a rotary engine having a wheel driven by the kinetic impact and reactive forces of a motive fluid which is adiabatically partially expanded in advance of the application of each of said forces, whereby the velocity of the wheel is 15 brought within safety and practical limits. In a divisional application for patent filed by me October 9, 1903, Serial No. 176,368, I have shown, described, and claimed a rotary engine embodying the above-stated adiabatic principle and consisting of a series of 20 wheels against each of which is directed an equal amount of energy of the motive fluid, which result is attained by a complete control of the velocity of the fluid throughout 25 the entire series of wheels, aided by the application of heat external to the stationary and moving parts, whereby the fluid throughout its traverse is maintained at a vaporizing 30 temperature. In other words, the stated 35 application of heat, which is accomplished through the medium of a steam-jacket, operates to prevent condensation of the steam at any point between its admission and discharge, thereby eliminating the friction 40 which would otherwise be obtained, and consequently to increase the general efficiency of the engine.

The present invention is an improvement upon the inventions forming the subjects- 45 matter of the applications above referred to, and the present improvements have for their object to increase the efficiency of the engine by the provision of what may be termed a "reheating-jacket," through which is con- 50 ducted the steam from which power is sub-sequently derived, the steam being admitted in the jacket toward the exhaust end of the engine and after traversing the jacket is delivered directly into the steam-chest. By this 55 provision the engine is subjected throughout to a uniform reheating temperature, derived

from the maximum temperature of the steam, which maximum temperature may, as hereinafter more fully explained, be the absolute temperature, or means may be provided for superheating the steam previous to its admission in the jacket, and in this connection it will be understood that my present turbine is designed for use in connection with steam the maximum temperature of which is 60 absolute or is superheated above the absolute 65 temperature.

A further object of my present invention is the provision of a rotary engine or steam-turbine having a set of stationary inclined diverging nozzles and a series of moving parts or wheels, each of which is equipped with impact-surfaces receiving the steam from said stationary nozzles, with a set of diverging nozzles inclined in a direction opposite to 70 that of the direction of inclination of the stationary nozzles and with a chamber interposed between the impact-surfaces and the wheel-nozzles and affording a passage for the steam from the impact-surfaces to and 75 through the wheel-nozzles, the steam issuing from the wheel-nozzles reacting against adjacent stationary abutments. By the employment of a moving part or wheel constructed in accordance with my present in- 80 vention the velocity of the steam in the wheel-nozzles is brought to exceed the steam velocity in the stationary nozzle, which ex- 85 cess velocity is due to the velocity of the steam through the wheel-nozzles plus the 90 velocity of the moving part or wheel. As- 95 suming, for example, that the velocity of the steam against the vanes or buckets of the moving part or wheel is nine hundred feet per second, the moving part or wheel receives from the impact of the steam at the stated velocity one-half such velocity, or four hundred and fifty feet per second. Entering 100 the wheel-nozzles from the moving chamber, the steam has a velocity which is nine hun- 105 dred feet a second plus the velocity of the wheel, or approximately thirteen hundred and fifty feet per second. Aside from the increased efficiency of the engine, due to the increased velocity of the steam at the reac- 110 tion-point, I am enabled to materially sim- plify the construction of engine by employ- 115 ing a less number of moving parts or wheels and intervening rest-chambers than are contemplated in the type of engine forming the subject-matter of my application for patent, Serial No. 176,368, above referred to.

Other advantages resulting from the improved construction forming the subject-matter of the present application are set forth in the following detailed description 5 of the construction and operation, in connection with which description reference is to be had to the accompanying drawings, which illustrate my improved rotary engine or steam-turbine in its preferred form of embodiment, it being understood that various 10 changes and modifications may be made therein without exceeding the scope of the concluding claims.

In the drawings, Figure 1 is a vertical central sectional view, partially broken away, 15 of a rotary engine or steam-turbine embodying my present invention. Fig. 2 is an enlarged detailed view of portions of the stationary and moving parts of the said rotary engine or steam-turbine.

Referring to the drawings by numerals, 1 designates the engine or turbine casing, in which are a series of wheels 2, keyed or otherwise fixed to a shaft 3, which is common to all of the wheels employed. At the 20 inlet end of the engine or turbine is a radial steam chamber or chest 4, the inner wall of which is formed by a ring 5, which is bolted or otherwise secured to the head 6 and preferably to an annular flange 7, formed integrally with the casing 1. In said flange 7 are a series of diverging nozzles 8, constructed and arranged to partially adiabatically expand the steam which enters 25 them from the steam chamber or chest 4.

The wheels 2 are each preferably formed of three disks 9, 10, and 11, bolted or otherwise secured together, and an annular rim 12, which rim is imperforate. The disk 9 of the 30 first wheel of the series is immediately adjacent to the flange 7, which carries the series of diverging nozzles 8. In each of the disks 9 is a concentric series of vanes or buckets 13, of concavo-convex form in cross-section 35 and constructed and arranged to provide between them diverging steam-passages. Each of the inner disks 10 terminate at or about the inner ends of the vanes or buckets, thereby providing an annular steam chamber or, 40 strictly speaking, passage, the walls of which are formed by the disks 9, 10, and 11 and the rim 12. This chamber or passage 14 is divided at intervals by partitions 15, set at an inclination, as shown in Fig. 2, and extending to the rim. The number of these partitions, and consequently the number of separate passages formed thereby, is dependent 45 upon the number of passages between the vanes or buckets which are common to one of the series of nozzles. In other words, the area 50 of the passage provided by the partitions will conform to the required number of passages between the vanes or buckets, and, further, these divided passages provide a separate 55 channel for each nozzle and prevent undue

expansion of the steam, which would otherwise occur in the event that certain of the series of nozzles are closed by the governing means. In each of the disks 11 are diverging nozzles 16, 16, communicating with the 60 divided chambers or passages and inclining in a direction opposite to the direction of inclination of the stationary nozzles 8, 8.

Between the wheels are annular chambers 17, which may be formed by the two-part ring 18 shown: In one of the walls of this chamber are a series of channels 19, into which steam is delivered from the wheel-nozzles 16, the passages 19 being formed and arranged to provide abutments against which 65 the steam issuing from the nozzles 16 reacts: After traversing the channels 19 the steam enters the stationary chamber 17 and is therein brought to a state of rest, after which it issues from the chamber through diverging 70 impact-nozzles 20, provided in the opposite chamber-wall. The further adiabatically-expanded steam issuing from the nozzles 20 impacts against the vanes or buckets of the next wheel of the series, which wheel or moving part is constructed similarly to the first wheel above described, and thereafter the operation is repeated throughout the series of 75 wheels, whereupon the steam exhausts at the point 21.

Assuming the initial velocity of the steam to be nine hundred feet per second, the first wheel of the series will receive by the impact of the steam at the stated velocity a peripheral velocity which is one-half the velocity 80 of the steam, or approximately four hundred and fifty feet per second. In traversing the passages or channels between the vanes or buckets the steam receives a further expansion and after traversing the divided chambers or passages in the wheel enters the wheel-nozzles 16, in which a further expansion 85 takes place. The steam leaving the nozzles 16 has a velocity equal to the initial velocity, or nine hundred feet per second plus 90 the velocity of the wheel. The steam impacting against the abutments of the channels 19 has therefore a velocity approximating 95 thirteen hundred and fifty feet per second and reacts against the wheel with a velocity which is one-half of that of the steam minus the wheel velocity. The wheel is therefore acted upon at each side by an equal amount of kinetic force, resulting in a perfect balance of the wheel between the two 100 applied forces—namely, that of impact and that of reaction.

Surrounding the engine or turbine casing is a steam chamber or jacket 22, into which steam is admitted directly from the steam-supply pipe 23. The steam-supply pipe leads into the jacket at a point toward the exhaust end of the engine, and said jacket 105 communicates at its opposite end directly with the steam chamber or chest 4. The 110

steam therefore previous to its utilization for power serves as the heating medium for creating and maintaining a degree of heat in the stationary and moving parts of the engine or turbine sufficient to maintain the steam throughout its traverse at the point of vaporization, and thereby prevent condensation, with the consequent friction and loss in efficiency. The location of the steam-inlet at the exhaust, or what is usually the coolest end of the engine, results in an equal distribution of heat throughout the engine or turbine parts and without materially lowering the maximum temperature of the steam. As previously stated, the steam may be admitted in the jacket at its maximum temperature, or means may be provided for super-heating the steam previous to its admission. In either event the efficiency of the engine is very largely increased, owing to the elimination of friction, which is otherwise present when condensation occurs, and by the re-heating effect of the steam-jacket the steam at the several points of impact and reaction is maintained at the most efficient temperature.

My improved engine or turbine is operated upon the adiabatic - expansion principle, which is fully explained in my applications hereinabove referred to, and a description of said principle in the present case is not thought to be necessary. It may be stated, however, that in the operation of the engine no loss of temperature of the steam results from the stated expansions, such loss occurring through the change in entropy of the fluid at the points of impact and reaction, the heat of the steam being absorbed at these points by the rotating parts, which absorptions are in proportion to the degrees of expansions created in the several nozzles. Following this step is the provision for reheating the steam at the several stages or, more properly stated, the prevention of loss of heat, with consequent condensation from external agencies. Not only, therefore, is the general efficiency of the engine materially increased by creating an equal amount of energy at each side of a wheel, but the full efficiency of the steam is obtained, with an absence of friction by the means for preventing loss of heat in the steam at the several stages. In addition, as above stated, the engine or turbine is materially simplified, with a consequent economy in construction.

Each of the moving parts or wheels is, as above described, formed of a number of parts or sections, although it is to be understood that the specific illustration and description is not to be regarded as a limitation, as the wheel may be variously modified. I prefer, however, to form each wheel of the separate parts, as by such construction the parts may be brought each to a true running balance previous to assemblage.

I claim as my invention—

1. In a rotary engine of the character described, moving parts each carrying vanes or buckets, reaction-nozzles and a series of passages between said vanes or buckets and said nozzles, a stationary part having an impact-nozzle arranged to discharge steam against said vanes or buckets, and stationary abutments against which the wheel-nozzles discharge. 75

2. In a rotary engine of the character described, a moving part having in one side vanes or buckets constructed and arranged to provide between them diverging channels, reaction-nozzles in the opposite side of the moving parts and an intervening steam-passage communicating with said channels and nozzles. 80

3. In a rotary engine of the character described, a series of moving parts, each provided in one side with vanes or buckets and in the opposite side with reaction-nozzles, passages carried by the wheels and communicating with the channels between the vanes or buckets and with said nozzles, a stationary impact-nozzle adjacent to the vanes or buckets of the first wheel, and rest-chambers between the wheels, each chamber having in one wall reacting-channels and in the opposite walls impact-nozzles. 90 95

4. In a rotary engine of the character described, a series of moving parts carrying impact-surfaces, and a series of sections of an adiabatic nozzle, each arranged to deliver the steam against the impact-surfaces of one of the moving parts, and all arranged to effect a continuous adiabatic expansion of the steam, and means for utilizing the steam before admission to said nozzles and parts for effecting a uniform heating thereof. 100 105

5. In a rotary engine of the character described, a series of moving parts carrying impact-surfaces, sections of an adiabatic nozzle each arranged to deliver steam against the impact-surfaces of one of said wheels, a steam-chest arranged to deliver steam to the first nozzle-section, and a steam chamber or jacket having an inlet and communicating with said steam-chest. 110

6. In a rotary engine of the character described, a series of moving parts carrying impact-surfaces, sections of an adiabatic nozzle, each arranged to discharge steam against the impact-surfaces of one of said wheels, a steam-chest, a steam-jacket communicating at one end with said chest, and a steam-pipe arranged to deliver into the other end of said jacket. 115 120

In testimony whereof I affix my signature in presence of two witnesses.
